UNITED STATES PATENT OFFICE.

HARRIET T. STUCKEY, OF MANNVILLE, SOUTH CAROLINA.

UMBRELLA-HOLDER.

SPECIFICATION forming part of Letters Patent No. 606,398, dated June 28, 1898.

Application filed June 18, 1896. Serial No. 595,996. (No model.)

To all whom it may concern:

Be it known that I, HARRIET T. STUCKEY, a citizen of the United States, residing at Mannville, in the county of Sumter and State of South Carolina, have invented certain new and useful Improvements in Umbrella-Holders; and I do hereby declare the following to be a full, clear, and exact description of the invention, such as will enable others skilled in the art to which it appertains to make and use the same.

My invention relates to improvements in umbrella-holders, the object of the same being to provide a device for attaching an umbrella to the body of a person so that both hands may be free.

The invention consists of a plate, padded on the inside, adapted to bear against the back, a tube or cylinder secured to the rear side of said plate, having means for attaching an umbrella therein, and means for securing said plate to the body of the wearer.

The invention is clearly illustrated in the accompanying drawings, in which—

Figure 1 represents a side elevation of the preferred form of my invention. Fig. 2 is a front view of the same. Fig. 3 is a longitudinal section on the line $x-x$ of Fig. 2. Fig. 4 is a cross-section.

Like reference-numerals indicate like parts in the different views.

My improved holder is made up of a plate or back piece 1, of tin, leather, or other suitable material, which is padded on the side which bears against the back of the wearer. On the rear of said plate 1 is secured a tube or cylinder 2, having internal screw-threads in its upper end, into which the lower end of an umbrella may be inserted and held. The front face of the plate 1 is padded, as shown, and is provided with loops 3 3 thereon, through which the back-bands of a pair of suspenders may be inserted for securing the plate to the back of the wearer.

By reason of the fact that the plate 1 is constructed of metal or leather a rigid support for the back is provided which will prevent the umbrella which is applied thereto from slipping away from the body. Said plate extends from the shoulders down to a point adjacent to the waist of the operator and provides a broad flat bearing-surface against the back.

From the foregoing description it will be seen that I have devised a simple and cheaply-constructed device for holding an umbrella over a man while at work which is readily applied and detached. It is provided with means whereby it may be connected to a pair of suspenders, which also perform their usual function of supporting the trousers, no separate or independent attaching means being necessary, except the loops 3 3, which project inwardly beyond the inner surface of the plate 1.

While I have described the umbrella as being adapted to be screwed into the upper end of the tube or cylinder 2, it is obvious that it may be fastened therein in any suitable way with means provided for adjusting the same up and down or at any desired angle. I have also described the plate 1 as being provided with loops through which suspenders are passed. This form of the invention would be applicable to men only. For women or men without suspenders I may have the plate 1 secured to a jacket fitting around the body, or straps may be secured to the top of the plate 1, which pass around the shoulders, and a second strap secured to the lower end of said plate, which passes around the waist.

Having now described my invention, what I claim as new, and desire to secure by Letters Patent, is—

An umbrella-holder, consisting of a plate of rigid material which is adapted to bear against the back of the operator and forms a broad bearing-surface extending from a point adjacent to the neck down to a point adjacent to the waist, and is provided with inwardly-extending loops through which the back-band of the suspenders which support the trousers of the operator are adapted to pass, and a tube or cylindrical portion secured to the rear of said plate, into which an umbrella is adapted to fit, as and for the purpose set forth.

In testimony whereof I have signed this specification in the presence of two subscribing witnesses.

HARRIET T. STUCKEY.
